TWO-CYCLE ENGINE

Edmond Pierre Robert Viel, Paris, France

Application August 10, 1945, Serial No. 610,060

8 Claims. (CL 123—69)

1 The present invention is relative to a two-cycle engine.

The principal objects of the invention are: to increase the engine efficiency of the two-cycle engines by ensuring a total expulsion from the cylinders of the burnt gases which have a tendency to remain there after each explosion, to allow of using any liquid or gaseous fuels, to lower the consumption of the said two-cycle engines and, as a result, the cost price of the horse-power-hour.

These objects and others will be apparent from the following description and the accompanying drawings given by way of example.

In said drawings:

Fig. 1 is a schematic view in elevation-section of a two-cycle single cylinder engine, the piston being supposed to be at its lowest dead point;

Fig. 2 is a partial view in profile section corresponding to that of Fig. 1;

Fig. 3 is a detailed view in section, showing the position of the distribution device when the piston is in course of compression;

Fig. 4 is a schematic view of an installation for the starting of the motor.

In referring to the Figures 1 to 3 of the drawings, 1 shows the cylinder of a two-cycle engine, 2 the piston and 3 the connecting rod joining the latter to the crank shaft 4 of the motor.

The cylinder 1 is provided on one part of its periphery and near its upper end, with vanes 5 forming a spiral and contriving, on the circumference of the said cylinder, a continuous pipe in spiral 6, watertight, obtained after the mounting of a cylindrical envelope 7 mounted by soldering, for example.

The lower end of the pipe 6 starts from a chamber 8, arranged between the external wall of the cylinder 1 and the internal wall of the envelope 7. Into this chamber 8 the fuel necessary for the working of the motor arrives by an orifice 9.

At its upper end the pipe 6 communicates by a tube 10 with a chamber 11 arranged in the escape tube 12 of the motor and in communication, by an orifice 13, with a chamber 14 formed above the said pipe between the cylinder 1 and the envelope 7. In its turn, the chamber 14 opens by a sprinkler 15 into a canal 16 pierced in the head 17 of the cylinder. The canal 16 ends at a chamber 18 from whence starts a pipe 19 ending in a chamber 20 from which, finally, starts a canal 21 delivering the fuel to the distribution device.

With the arrangement which has just been described any fuel, even in a liquid state, penetrat-

ing in the chamber 8, arrives gasified in the canal 21, under pressure and warmed.

In order to maintain the gasified fuel arriving in the canal 21 at a suitable pressure, a device for regulating the pressure 22 communicates with the chamber 18. This device has for its part, in case of surpressure of gasified fuel, to allow this fuel to pass from the chamber 18 to the chamber 23 of the said device, from whence it can be evacuated towards the fuel tank by piping mounted in the orifice 24.

The distribution device is formed by a rotary tap 25 provided with two cells opposite each other, 26 and 27, and lodged in a corresponding hollow 15 in the cylinder head 17. It is in this hollow that the canal 21 comes, as well as canal 28 intended for the admission of compressed air supplied by a compressor 29. The starting of the rotation of the tap 25 is effected from the driving shaft 4 by means of three toothed wheels or pinions 30, 31 and 32. The tap 25 thus turns in the same sense as the driving shaft 4.

The motor is completed on the one hand by a needle valve 33, with spring 34, acting in the chamber 28 and allowing of closing the outlet orifice of the canal 19 and, on the other hand, by a pivoting shutter 35 allowing of controlling the escape of the burnt gases.

The working of the two-cycle engine described is the following:

The fuel, liquid for example, being admitted into the chamber 8 by the orifice 9 rises in the pipe 6 to pass into the chamber 11 by the tube 10. From the chamber 11 it goes to the chamber 18 by the orifice 13, the sprinkler 15 and the canal 16. From the chamber 18 the said fuel finally goes to the admission canal 21 by the pipe 19 and the chamber 20. It is to be noted that the fuel, between its entry into the chamber 8 and its arrival in the admission canal 21, being always in contact with warm walls becomes gasified in the course of its passage to arrive at the said canal 21 completely gasified, under pressure and warmed.

It will be quite understood that if the fuel is already in a gaseous state at the moment of its admission, its travelling in the envelope of the cylinder has as its only effect its warming in putting it under pressure.

The tap 25 and the piston 2 being in the position of the Fig. 2, the compressor 29 delivers, by the canal 28 and the cell 27, compressed air into the cylinder 1, whilst the cell 26 is filled with combustible gas under pressure.

The cell 27 allows of the entry of compressed

air into the cylinder from the moment that the escape orifice opens until after its closing. This compressed air, then, commences by completely clearing the cylinder of the burnt gases which it contains, then partially fills the said cylinder.

The piston continuing its upward course, the tap 25 turns in such a way that the gasified fuel contained in its cell 26 penetrates in its turn into the cylinder where it mixes with the compressed air therein contained and forms with this latter 10 the detonating mixture which explodes as soon as the piston reaches its high dead point.

When the piston arrives at the point of thereafter and afresh uncovering of the escape orifice, the cell 27 is in position to allow of the arrival 15 of compressed air, whilst the cell 26 has just filled itself with gasified fuel under pressure and warmed, and the cycle described recommences.

It results from that which precedes that the two cells 26 and 27 serve alternatively to the successive introduction into the cylinder of the two constituents of the detonating mixture, to wit: compressed air and fuel gasified, under pressure and warmed.

When the motor is working all pressure of gasified fuel above a predetermined value gives rise to the setting in action of the pressure regulator 22 which, when it is open, allows of the evacuation from the chamber 18 of a portion of the fuel which it contains, by the chamber 23 and the opening 24.

When the motor is stopped any leaking of fuel is prevented by means of the needle valve 33 lodged in the chamber 20 which can come to close the entrance opening of the canal 21 under the action of any appropriate exterior control.

In order that the motor may run, especially by means of a liquid fuel, it is necessary that it should be brought to a temperature sufficient to ensure by itself the gasification, the bringing under pressure and the warming of the said fuel. It is therefore necessary to provide, for the starting of the motor when cold, a starting installation which may be that of the type represented in the Fig. 4.

In the said installation, 36 indicates the motor properly so-called, 29 the air compressor and 22 the pressure regulator already described, the said compressor and regulator being, for the clearness of the drawing, supposed to be apart from the motor, whereas, as a matter of fact, they are mounted on the latter.

As appears from Fig. 4, the fuel is delivered to the chamber 8 of the motor by a pump 37, drawing up the said fuel, contained in a tank 38 by piping 39 and sending it back towards the chamber 8 by a piping 40. At the upper part of the tank 38 a piping 41 comes out which, coming from the opening 24 of the regulator 22 allows, in case of over pressure, to bring the fuel escaping from chamber 18 back to the said tank.

For the starting properly so-called there is available a bottle of compressed air 43 and a bottle 44 of combustible gas under pressure, these two bottles being each provided with a regulating sluice tap 45 and 46 respectively. The bottle 43 is connected by a pipe 47 to the entrance to the canal 28 whilst the bottle 44 is connected by a pipe 48 to the chamber 18.

The installation is completed by a wing tap 49 70 for the regulation of the pressure of the air supplied by the compressor 29, the said wing tap being subject to the action of a control 50.

For starting the motor running the compressed air supplied by the bottle 43 and the combustible 75

gas supplied by the bottle 44 are used. After the motor has been running for a certain time, time sufficient to allow of the latter becoming sufficiently warmed, the outlets of the bottles 43 and 44 are cut off and the motor is fed from the tank 38 and with the compressor 29.

The motor described can work either with a medium degree of compression or with a high degree of compression largely exceeding ten.

In the first case the admission is made completely during the greater part of the ascending movement of the piston 2, the compression then being realised under conditions sensibly similar to those which exist in the present motors comprising an ignition device.

In the second case, the regulation of the distribution is established in such a manner that the cells 26 and 27 do not enter into communication with the interior of the cylinder 1 except at a moment which precedes by very little the point of advance to the ignition. The necessity of an ignition is thus done away with (case of the drawings) and the motor described combines the advantages of the explosion motor and those of the injection motor.

The regulation of the carburetion may be carried out by causing the relation air-fuel to vary during the running of the motor, that is:

(a) by modifying the pressure of the fuel by action on the pressure regulator 22;

(b) by braking, with the wing tap 49, the arrival of the air to the compressor 29.

In the same way, the regulation of the outgoing speed of the escaping gases is done by the wing tap 35. As to the variation in the advance of ignition, it is obtained by the usual controls, whereas the variation in the stoppage of the distribution is carried out by means of an endermic control acting on the shaft of the rotary tap 25.

The working of the various regulating controls not being able, practically, to be carried out separately and with precision in the minimum of time, it would be advantageous to provide for a single control allowing of ensuring the simultaneous manoeuvring of all the controls. By way of example, the manoeuvring of the various controls might be ensured by a cam shaft, set in rotation by the single control, the profile of the cams activating tappets acting on the controls, being arranged in such a manner that a maximum output would be obtained with the different variations of the motor.

It is obvious that the invention is in nowise limited to the embodiment which has been more especially described by way of example, but that it extends to all possible modifications coming, fairly, within the scope of the appended claims.

I claim:

1. A two-cycle engine comprising a rotary tap with two cells mounted in a recess provided in the cylinder head and in communication with said cylinder, two conducts ending in said recess and adapted to deliver therein compressed air and a fuel gasified, under pressure and warmed, respectively, means supplying said conducts with compressed air and fuel and means driving in rotation said rotary tap from the driving shaft of the motor.

2. A two-cycle engine comprising a rotary tap with two opposite cells mounted in a recess provided in the cylinder head and in communication with the cylinder, two conducts ending in said recess and in communication respectively with an air compressor and with the outlet end of a circuit formed by a series of chambers and

canals in direct contact with the warm walls of said cylinder, means supplying a fuel to the inlet end of said circuit and means driving in rotation said rotary tap from the driving shaft of the engine.

3. A two-cycle engine comprising a rotary tap with two cells mounted in a recess provided in the cylinder head and in communication with the cylinder, two conducts ending in said recess and in communication respectively with an air compressor and with the outlet end of a circuit formed by a series of chambers and canals in direct contact with the warm walls of said cylinder, means supplying a fuel to the inlet end of said circuit, a regulator pressure device in communication with said circuit and with a return pipe for the fuel and means driving in rotation said rotary tap from the driving shaft of the engine.

4. A two-cycle engine according to claim 3 wherein the regulator pressure device communicates with one of the two chambers the nearest preceding the conduct for the admission of fuel into said recess.

5. A two-cycle engine comprising a rotary tap with two opposite cells mounted in a recess provided in the cylinder head and in communication with the cylinder, two conducts ending in said recess and in communication respectively, with an air compressor and with the outlet end of a circuit formed by a series of chambers and canals in direct contact with the warm walls of the cylinder, a pump supplying a fuel to the inlet end of said circuit, a regulator pressure device in communication with said circuit and with a return pipe for the fuel, a needle valve controlling the conduct for the admission of fuel in said recess and means driving in rotation said rotary tap from said driving shaft of the engine.

6. A two-cycle engine comprising a rotary tap with two opposite cells mounted in a recess provided in the cylinder head and in communication with the cylinder, two conducts ending in said recess and in communication respectively, with an air compressor and with the outlet end of a circuit formed by a series of chambers and canals in direct contact with the warm walls of the cyl-

inder, a pump supplying a fuel to the inlet end of said circuit, a regulator pressure device in communication with said circuit and with a return pipe for the fuel, a needle valve controlling the conduct for the admission of fuel in said recess, a regulating shutter at the outlet end of the escape tube and means driving in rotation said rotary tap from the driving shaft of the engine.

7. A two-cycle engine comprising a rotary tap with two opposite cells mounted in a recess provided in the cylinder head and in communication with the cylinder, two conducts ending in said recess and in communication, respectively, with an air compressor provided with a regulator device for the pressure, and with the outlet end of a circuit formed by a series of chambers and canals in direct contact with the warm walls of the cylinder, a pump supplying a fuel to the inlet end of said circuit, a regulator pressure device in communication with said circuit and with a return pipe for the fuel, a needle valve controlling the conduct for the admission of fuel in said recess, a regulating shutter at the outlet end of the escape tube and means driving in rotation said rotary tap from the driving shaft of the engine.

8. An installation for starting the running of the two-cycle engine according to claim 1, comprising a bottle of compressed air with a sluice tap in communication with the conduct for the admission of compressed air in the rotary tap and a tank of gaseous fuel in communication with the conduct for the admission of fuel in the rotary tap.
